UNITED STATES PATENT OFFICE.

JOHN EMORY BERKSTRESSER, OF MONTEVALLO, ALABAMA.

POOL-TABLE.

SPECIFICATION forming part of Letters Patent No. 650,775, dated May 29, 1900.

Application filed October 17, 1899. Serial No. 733,915. (No model.)

To all whom it may concern:

Be it known that I, JOHN EMORY BERKSTRESSER, a citizen of the United States, residing at Montevallo, in the county of Shelby 5 and State of Alabama, have invented a new and useful Pool-Table Attachment, of which the following is a specification.

The invention relates to improvements in pool-table attachments.

One object of the present invention is to improve the construction of pool-table attachments for collecting the balls after the same have been pocked and to provide a simple and comparatively inexpensive one adapted 15 to be readily applied to a pool-table and capable of enabling the balls pocked by two players to be held separate and in position, so that the condition of a game may be readily ascertained at a glance.

A further object of the invention is to enable the separated balls to be quickly collected after a game has been completed, so that they may be conveniently replaced on the table for another play.

Another object of the invention is to enable a cue-ball to be readily separated from the other balls should it become accidentally pocked and to provide means for indicating whether the pocked balls are being properly conducted to the player who made them.

The invention consists in the construction and novel combination and arrangement of parts hereinafter fully described, illustrated in the accompanying drawings, and pointed 35 out in the claims hereto appended.

In the drawings, Figure 1 is a plan view of a pool-table provided with an attachment constructed in accordance with this invention, a portion of the table being broken away to 40 show the central ball-receptacle and the tubes or conductors connected therewith. Fig. 2 is a longitudinal sectional view. Fig. 3 is an end elevation. Fig. 4 is a detail view of a portion of the table, showing one of the side pockets.

Fig. 5 is an enlarged sectional view of the central ball-receptacle, the section being taken longitudinally of the table. Fig. 6 is a similar view taken at right angles to Fig. 5. Fig. 7 is a detail perspective view of one of the end 45 cut-offs. Fig. 8 is a detail sectional view illustrating the construction of the outer ends of the operating-rods.

Like numerals of reference designate corresponding parts in all the figures of the drawings:

55

1 designates outer longitudinal ball-conductors, consisting of semitubular troughs and located at opposite sides of a pool-table 2 and inclining downward from the corner pockets 3 to the side pockets 4 and adapted to 60 conduct balls from the ends of the table to points beneath the side pockets. The side and corner pockets are open at their bottoms to cause the balls pocked to be deposited in the ball conductors or troughs 1, which are 65 connected with central transverse ball conductors or troughs 5, extending from points beneath the side pockets to a central conical ball-receptacle 6, located beneath the center of the table and suitably secured to the same. 70 The inner ends of the transverse ball-conductors communicate with the interior of the central tapering ball-receptacle, at points between the top and bottom thereof, and the bottom 7 of the receptacle 6, which is open, 75 is sufficiently contracted to cause the balls to pass through it one at a time successively.

Extending from the central receptacle to one end of the table and adapted to receive balls from the central receptacle are ball-conductors 8 and 9, consisting, preferably, of semi-tubular troughs, but the various ball-conductors may be made of complete tubes or any other construction may be provided. The inner ball-conductors 8 diverge from the central receptacle and extend to the foot of the table and are connected at their outer ends to outer transversely-disposed ball-conductors 10, which are adapted to collect the balls and hold the same in full view of the players until the game is completed, so that the condition of the game may be ascertained at a glance at any time. The lower adjacent ends of the outer transverse collecting troughs or conductors 10 communicate with a main basket or receptacle 11, suspended from the adjacent end of the table and adapted to hold the balls when a game is not in progress. The conductors or troughs 10 are provided adjacent to the baskets with cut-offs 12, consisting of levers, each of which is fulcrumed at its rear end at 13 and is provided between its ends with a depending arm 14, having an elastic sleeve of rubber or other suitable 90 95 100

material to prevent it from chipping or otherwise injuring the balls. The outer end of the lever is provided with a suitable handle and is adapted to be raised to permit the 5 balls to run into the main basket or receptacle. The other inner longitudinal conductor 9 extends from the central receptacle to a basket or receptacle 15, located at the head of the table and adapted to receive the cue-ball of a player should it become accidentally pocketed, the passage of the balls being controlled as hereinafter described.

The lowermost ball of the central tapering receptacle is supported, as illustrated in Fig. 15 5 of the accompanying drawings, by arms of levers 16, 17, and 18, which are adapted to be oscillated to cause a ball to drop out of the receptacle at that side and fall into the corresponding inner ball conductor or trough. 20 The lever 16, which is fulcrumed between its ends, controls a central inner longitudinal conductor or trough 19, which extends directly from the central receptacle to the main end receptacle 11 and is adapted to convey 25 during a game a ball to the said receptacle 11, so that it may be resotted when necessary. The lever 17, which is constructed similar to the lever 16, controls the passage of balls to the inner ball-conductor 9, and the 30 levers 18, which are fulcrumed at their upper ends at opposite sides of the conical or tapering receptacle 6, control the passage of balls to the diverging conductors 8. The inner faces of the arms of the ball-supporting levers 16, 17, and 18 are provided with a suitable lining or covering to prevent them from injuring the balls. The side levers 18 are connected at points between their ends to operating-rods 20, which extend to the foot of 35 the table and which have their outer ends located at opposite sides of the center of the same, as clearly illustrated in Fig. 3 of the accompanying drawings. The levers 16 and 17 are pivoted at their upper ends to rods 21 40 and 22, extending to the ends of the table, at the center thereof, and each rod is provided at its outer end with a head 23 and is engaged by a coiled spring 24, interposed between the head and the table and adapted to 45 maintain the levers in position for supporting the balls. The springs are preferably housed within recesses 25 of the table, but they may be arranged in any suitable manner, and it will be apparent that by forcing 50 an operating-rod inward its corresponding lever will be oscillated and the passage of the balls from the central receptacle will be controlled.

In order to enable the players to tell readily 60 whether the balls are being delivered to the proper collecting tube or conductor, bells 26 are provided and arranged at points intermediate of the ends of the diverging tubes or conductors 8 and are designed to be of different tones, so that they may be readily distinguished from each other. Each bell is

provided with an operating-lever 27, extending into the adjacent tube or conductor and arranged in the path of the balls, so that the bell will be rung by each of the balls traveling through the tubes, troughs, or conductors, all of which are designed to have sufficient inclination to cause the balls to move at the desired speed and with the necessary force, so that there is no liability of the balls 75 collecting in the diverging conductors at the bell-levers, as might be the case if the balls had not sufficient force to operate the bells.

It will be seen that the attachment is simple and comparatively inexpensive in construction and adapted to be readily applied to a pool-table, that it will obviate the necessity of the players keeping account of the pocketed balls, and that it will enable the condition of the game to be readily ascertained at a glance. It will also be apparent that it will enable the balls to be collected without walking around the table and that the main receptacle 11 will hold the balls until they are wanted for play, thereby obviating the necessity of providing racks for the reception of the balls.

Changes in the form, proportion, size, and the minor details of construction within the scope of the appended claims may be resorted to without departing from the spirit or sacrificing any of the advantages of this invention.

What is claimed is—

1. A device of the class described comprising a central receptacle, conductors connecting the central receptacle with the corner and side pockets, the diverging inner conductors 8 extending from the central receptacle to one end of the table, the outer transverse conductors 10, located at one end of the table and adapted to collect the balls and communicating with the outer ends of the conductors 8, the outer receptacle 11 arranged at the inner ends of and communicating with the outer transverse conductors 10, the outer receptacle 15, located at the opposite end of the table, the central longitudinal conductors 9 and 19 connecting the receptacles and means for controlling the passage of balls 115 from the central receptacle to the conductors leading therefrom, substantially as described.

2. A device of the class described comprising the outer side conductors extending from the corner pockets to the side pockets, a central receptacle, the central transverse conductors extending from the side conductors to the said receptacle, the diverging inner conductors 8 extending to one end of the table, the outer transverse conductors adapted to collect the balls, the outer receptacle 11 communicating with the outer transverse conductors, the outer receptacle 15 located at the opposite end of the table, the central longitudinal conductors connecting the receptacles, and means for controlling the passage

of balls from the central receptacle to the conductors leading therefrom, substantially as described.

3. A device of the class described comprising a receptacle designed to be arranged centrally beneath a pool-table and provided at its bottom with an opening, the central longitudinal conductors extending from the central receptacle, the diverging conductors also extending from the central receptacle and located at opposite sides of one of the longitudinal conductors, the levers 16 and 17 located at the inner ends of the longitudinal conductors for controlling the passage of balls to the same, and fulcrumed at their upper ends on the receptacle at the bottom thereof, said levers 16, 17 and 18 having their lower portions converging downward beneath the opening of the bottom of the receptacle, and means for operating the levers, substantially as described.

4. A device of the class described comprising a central receptacle provided at its bottom with an opening, conductors extending from the central receptacle to the corner and side pockets, the diverging inner conductors

8 extending from the central receptacle to one end of the table, the outer transverse conductors 10 communicating with the outer ends of the conductors 8, the outer receptacle 11 arranged at the inner ends of and communicating with the outer transverse conductors 10, the outer receptacle 15 located at the opposite end of the table, the central longitudinal conductors 9 and 19 connecting the receptacles, the levers 16 and 17 located respectively at the inner ends of the conductors 19 and 9 and fulcrumed between their ends on the receptacle, the side levers 18 fulcrumed at their upper ends on the receptacle at the bottom thereof and located at the inner ends of the diverging conductors 8, said levers 16, 17 and 18 having their lower portions converging downward beneath the opening of the bottom of the receptacle, the operating-rods 21 and 22 connected with the upper ends of the levers 16 and 17, and the operating-rods connected with the levers 18 at points between the ends thereof, substantially as described.

In testimony that I claim the foregoing as my own I have hereto affixed my signature in the presence of two witnesses.

JOHN EMORY BERKSTRESSER.
